UNITED STATES PATENT OFFICE

132,319

DESIGN FOR A SUCTION CLEANER OR THE LIKE

Charles H. Taylor, Springfield, Mass., assignor to
Westinghouse Electric & Manufacturing Com-
pany, a corporation of Pennsylvania

Application September 4, 1941, Serial No. 103,150

Term of patent 14 years

To all whom it may concern:

Be it known that I, Charles H. Taylor, a citizen of the United States, residing at Springfield, in the county of Hampden and State of Massachusetts, have invented a new, original, and ornamental Design for a Suction Cleaner or the like, of which the following is a specification, reference being had to the accompanying drawing, forming a part thereof.

Fig. 1 is a side perspective view of a suction cleaner embodying my design, the dust bag being omitted for clarity of illustration.

Fig. 2 is a front perspective view of the same. The side of the suction cleaner not shown is substantially the same as the side shown in Fig. 1, except, there is no exhaust outlet on the side not shown.

The dominant feature of the design is shown in solid lines on the drawing.

I claim:

The ornamental design for a suction cleaner or the like, substantially as shown and described.

CHARLES H. TAYLOR.
